UNITED STATES PATENT OFFICE.

ALFRED LABRAM, OF OSTERLEY PARK, ENGLAND, ASSIGNOR TO WHITING-PATTERSON CO., INC., A CORPORATION OF PENNSYLVANIA.

DESIGN FOR COVER PAPER OR SIMILAR MATERIAL.

Application filed September 15, 1927, Serial No. 23,425, and in Great Britain May 16, 1927. Term of patent 3½ years.

To all whom it may concern:

Be it known that I, ALFRED LABRAM, a subject of the King of England, residing in Osterley Park, Middlesex, England, have invented a new, original, and ornamental Design for Cover Paper or Similar Material, of which the following is a specification, reference being had to the accompanying drawing, forming a part thereof.

In the drawing, the figure is a view of a

portion of cover paper or similar material, showing my new design, a complete unit of which, repeated indefinitely throughout the design, is enclosed between the broken lines A—A and B—B.

I claim:

The ornamental design for cover paper or similar material as shown and described.

ALFRED LABRAM.
